UNITED STATES PATENT OFFICE.

BLAINE H. HARRIS, OF ST. PAUL, MINNESOTA, ASSIGNOR TO BROWN & BIGELOW,
OF ST. PAUL, MINNESOTA, A CORPORATION OF MINNESOTA.

CALENDAR-PAD RETAINER.

Application filed June 23, 1921. Serial No. 479,858.

To all whom it may concern:

Be it known that I, BLAINE H. HARRIS, a citizen of the United States, residing at St. Paul, in the county of Ramsey and State 5 of Minnesota, have invented a new and useful Improvement in Calendar-Pad Retainers, of which the following is a specification.

This invention relates to means for holding the sheets which form the calendar pad 10 against free disengagement from their retaining pocket which is formed on the cover of the casing of a memorandum pad holder. The cover is hingedly secured to the casing and is adapted to close the same to 15 conceal the sheets of the memorandum pad holder therein. In use the casing can be closed readily by the cover. Heretofore the cards which form the sheets of the calendar pad were held freely in a pocket formed on 20 the cover for the same. Where the sheets of the calendar pad are freely held in the pocket on the cover they slide out of the same very readily, making it annoying in handling the pad-retaining case.

25 This invention provides means formed from the body of the cover forming a spring or resilient engaging tongue which presses against the back of the sheets of the calendar pad to form sufficient friction to hold the 30 cards or sheets of the calendar pad in position on the pocket on the cover to prevent them from falling out or becoming displaced while opening and handling the memorandum case. In making the cover 35 the pad-retaining tongue is formed without extra operation or material which simplifies and reduces the cost of making the pad-retaining means. This is essential in a device of this nature.

40 The pad-retaining means does not mar or detract from the general appearance of the memorandum case, it being practically invisible from view when the same is open and in use. Articles of this nature are ordinarily used on a desk and it is desirable 45 to have them of an attractive design with a neat appearance. It is very essential that the cards or sheets which form the calendar pad are held so that they can be readily 50 changed and adjusted in position, yet they must not slide freely out of the pocket in which they are held.

In the drawing forming a part of this specification:

55 Figure 1 is a perspective view of the

memorandum pad case as it would appear in use.

Figure 2 is a perspective view of the case when closed.

Figure 3 is a section on the line 3—3 of 60 Figure 2 in enlarged form, illustrating only a portion of the case.

The case A is of a rectangular nature having a bottom 10 and side walls 11 with rear and front ends 12 and 13 respectively. 65

A pad of memorandum sheets B are loosely disposed and adapted to be contained in the case A in a manner so that they can be readily removed a sheet at a time or as 70 may be desired.

The casing A forms means for holding the sheets 14 of the pad freely disposed upon each other but against being scattered about or misplaced.

The cover 15 is hingedly secured at 16 to 75 the sides 11 of the casing and is provided with a calendar pad pocket 17 which is secured to the inner face thereof. The pocket 17 forms a recess for receiving one end of the sheets 18 which form the calendar pad C. 80

The sheets 18 form the monthly pad. A series of larger sheets 19 are positioned in back of the sheets 18 and extend above the same. These sheets illustrate the name of 85 the month and the days of the week.

It is desirable to have the sheets of the pad C readily removable so as to change the months indicated. The end of the sheets 18 which extend into the pocket 17 have printed thereon some of the months of the year 90 which are concealed within the pocket. These cards can be reversed so as to indicate the other months and by so arranging the cards only a small number are necessary for 95 the year.

It is obvious that the desired number of cards may be used in the pocket 17, but it is the essence of this invention to provide engaging and holding means which is associated with the pocket in a manner to engage the cards or sheets of the pad C to hold them from falling out of the pocket. This is accomplished by the spring tongue 20 which is formed from the body of the cover 15. The tongue 20 extends directly in back of the pocket 17 and is curved inwardly to provide a resilient engaging means which frictionally holds the sheets of the pad B firmly in the pocket 17. The association of the tongue in relation to the pocket firmly. 100 105 110

engages the sheets 18 and 19 to prevent them from sliding out or becoming displaced, yet allowing the sheets to be removed when desired so that they can be re-positioned at any time.

The invention is designed to provide a simple practical inexpensive means for engaging the sheets of the calendar pad to hold them in place without changing or marring the appearance of the desk utility when in use. It is readily apparent that it is essential that the sheets of the pad should not freely slide out of the pocket. The variation in the thickness of paper or other material which may be used for the sheets of the calendar pad makes it desirable to have a yieldable engaging means which will conform to the thickness of the sheets and act to hold the same in place in a practical manner. Thus the engaging means associated with the pad pocket holds the sheets so that they will not fall out while the memorandum case is being handled and before it is set up for use.

25 I claim

1. In combination with a desk pad holder

having a cover hingedly secured thereto, a calendar pad pocket on said cover and means associated with said pocket adapted to hold the calendar pad therein against 30 freely sliding out of said pocket.

2. A holder for a calendar pad associated with a memorandum pad case including a cover member hingedly secured to said case, a member secured to the inner face of said cover adapted to form a pocket for receiving the sheets of the calendar pad and a spring tongue formed from the body of said cover and positioned in a manner to co-operate with the member secured to said cover 40 to hold the sheets of the pad against sliding out of the pocket.

3. A memorandum pad case, including a receptacle for memorandum sheets, a cover hingedly secured to said receptacle, a pad-receiving pocket secured to said cover and resilient means associated with said pocket adapted to hold sheets inserted in said pocket against freely sliding out of the same.

BLAINE H. HARRIS.
